PORTABLE CUP ASSEMBLY

Ray H. Sayre, Emsworth, Pa.

Application February 28, 1940, Serial No. 321,295

3 Claims. (Cl. 224—45)

My invention relates to drinking cups, and consists in an unit assembly of cups in a portable carrier, which carrier, conveniently, is also adapted to support a stack of saucers.

The structure of the invention is of artistic and pleasing appearance; it includes a stand or carrier adapted primarily for the support of a plurality of cups and incidentally for the support of a stack of saucers that are used with the cups in service. The stand and the supported cups and saucers are readily portable as a unit, and, as such, the assembly is of particular value to the hostess at bridge luncheons and the like. It is characteristic of the assembly that the cups are snugly nested one within another in a line, and the line is secured against displacement on a suspension rod. The cups, even though they are, as said, assembled in contact with one another, cannot rattle or clash in such manner as to chip the rims of the cups or their handles. In the realization of a unit assembly possessing of utility of the nature indicated, I bring into new association several structural refinements. One of such refinements is found in the structure of the cups per se, and the others in the structure of the carrier or stand.

In the accompanying drawing an embodiment of the invention is shown in perspective.

Referring to the drawing, the carrier structure is, conveniently, made of wood, and the base is formed of two blocks 1 and 2, mortised and integrated in the shape of a cross. Extending upward from the base 1, 2 is a member 3, and at a substantial interval above the base is an elongate, horizontal, flexible rod 4. The rod 4 is firmly anchored at its left-hand end in the member 3, and provides a cantilever support for a horizontally nested group of cups C.

The cups, as may be understood from what has been said before, are peculiarly adapted for nested suspension in the particular carrier. Specifically, I use cups whose perforate handles extend from the side of each cup in parallelism with the plane of the cup's rim. By virtue of such departure from cups having the ordinary vertical handles, the several cups are adapted to be nested compactly in a horizontal line, a line extending laterally from the upright carrier member 3 and suspended on rod 4.

It will be understood that the rod 4 extends through the aligned perforations in handles h of the cups, and that the cups are readily removable from the carrier by slipping them, one after another, from their nested position on the rod 4.

The upright member 3 is rigidly secured to one

end of the basal block 1 of the carrier, and it may be noted that the base may be employed as a support for a stack of saucers S. A vertical post 5 is provided at each end of the base block 2, and these posts 5, together with the lower body portion of member 3, serve to secure the saucers S in accurately stacked position on the base 1, 2.

Advantageously, the upright member 3 is continued at its upper end in a horizontally extending arch position 3a, and this arch portion, extending in common vertical plane with the suspension rod 4, provides a handle, whereby the unit assembly may be readily transported.

In refinement, the distal end of flexible rod 4 is arranged yieldingly to engage, from below, the otherwise free terminal 3b of the handle portion 3a of the carrier, thus preventing accidental dislodging of the supported cups. The elongate, cantilever rod 4 comprises a bar of wood or metal of substantial resilience, and it is anchored in such position in member 3 that the distal end of the bar engages the end 3b of the handle portion 3a in the desired manner. The rod 4 sustains the dead weight of the group of cups, and sustains the weight of the cups augmented by the effect of inertia, as the carrier is lifted and carried in the hand. In installing or removing cups, the rod 4 is pressed downward, so that its distal end is removed from engagement with the handle portion a sufficient interval to permit passage of the cup handles.

The application for this patent comprised a continuation in part of application Serial No. 35 142,768, filed May 15, 1937.

I claim as my invention:

1. A portable carrier for a line of nested cups having perforate handles arranged in alignment, said carrier comprising a base upon which the carrier is adapted to stand upon a supporting surface, a support member extending upward from said base, a rod secured at one end to said support member at a point spaced at an interval above said base, said rod extending as a cantilever from said support member and adapted to receive the aligned handles of a nested group of cups, said support member being continued above said rod in an arched portion that extends upward from and over said rod and then downward to a point adjacent to the distal end of said rod and providing a detent effective in prevention of the unintentional removal of cups from the rod, the body of said arched portion providing between the distal end of said rod and the point of union of the rod with said support

member a handle by means of which the carrier and the articles assembled thereon may be lifted and transported in the hand.

2. A portable carrier for a line of nested cups having perforate handles arranged in alignment, said carrier comprising a base upon which the carrier is adapted to stand upon a supporting surface, a support member extending upward from said base, an elongate substantially horizontal rod secured at one end to said support member at a point spaced at an interval above said base, said rod extending as a cantilever from said support member and adapted to receive the aligned handles of a nested group of cups, said support member being continued above 15 said rod in an arched portion that extends upward from and over said rod and then downward to a point adjacent to the distal end of said rod and providing a detent effective in prevention of the unintentional removal of cups from the 20 rod, and the body of said arched portion providing between the distal end of said rod and the point of union of the rod with said support member a handle by means of which the carrier and the articles assembled thereon may be lifted and 25 transported in the hand, the body of said cantilever rod being sufficiently rigid to sustain not

only the dead weight of a line of cups, but the weight of the line augmented by inertia when the carrier is lifted and carried in the hand, and yet sufficiently elastic to yield under applied pressure, to admit of the movement of the distal end of the rod into cup-releasing position relatively to the detent-forming end of said arched portion.

3. A portable stand for the support of a line of cups that have perforate handles paralleling the rims of the cups and that are compactly nested one within another in breakage-preventing assembly, with the perforations in the handles aligned; said portable stand comprising a base, an upright rising from said base, means for suspending the line of nested cups comprising an elongate rod extending laterally from the upright and adapted to receive the aligned handles of the nested cups, said upright being provided with a transversely-extending handle-forming portion at an interval above said rod, the distal end of said handle-forming portion cooperating with the distal end of said rod in normally securing the line of cups in suspended position on the rod.
